BY *Arno Zillger*
Cyrus W. Anderson
ATTORNEY.

UNITED STATES PATENT OFFICE.

ARNO ZILLGER, OF NARBERTH, PENNSYLVANIA, ASSIGNOR TO MUSIC MASTER CORPORATION, OF PHILADELPHIA, PENNSYLVANIA, A CORPORATION OF DELAWARE.

STATION-RECORDING MEANS FOR RADIO RECEIVING DEVICES.

Application filed December 9, 1924. Serial No. 754,767.

My invention relates to signal receiving means for radio receiving apparatus and it has for its general object to provide a novel construction of means associated with an adjustable element of the said apparatus whereby when said element is adjusted to obtain signals from a sending or broadcasting station the position thereof at final adjustment may be indicated and recorded.

It is also an object of the invention to provide a novel construction of means of the character indicated which comprises simplicity and efficiency and which may be embodied in the structure of a radio signal receiving set or apparatus without disorganization of the construction of said apparatus.

To these and other ends the invention comprehends the construction and arrangement of parts as hereinafter described in detail, particularly pointed out in the claims, and as illustrated in the accompanying drawing in which I have shown one convenient form of mechanical embodiment of the said invention. However, it will be understood that the invention is susceptible of embodiment in other forms than that shown and that changes in the details of construction may be made within the scope of the claims without departing from the principle of the said invention.

In the drawing, Fig. 1 is a sectional side elevation taken on the line 1—1 of Fig. 2; and

Fig. 2 is a transverse horizontal sectional view taken on the line 2—2 of Fig. 1.

Referring to the drawing:

1 designates the front panel of insulating material of a radio signal receiving set or apparatus upon which various parts and elements of said apparatus are mounted.

In the use of radio signal receiving apparatus it is, as is well known, necessary to adjust certain parts or elements thereof in order to condition the apparatus so as to adjust it for the receiving of Hertzian waves from distant points or stations. The condenser in such apparatus is one of the elements which is adapted to be adjusted for that purpose. To condition the apparatus, as above indicated, and for the purpose of illustrating and indicating the principle of my invention I have shown a condenser in the present instance.

The device embodying my invention is

adapted to indicate the position of the condenser or other movable element of the apparatus when final adjustment thereof has been attained so that in case it is desired to employ the apparatus for interception of signals from the same station at a future time the adjustable element may be repositioned at such point without experimentation and without difficulty.

The condenser is indicated as a whole at 2 and comprises stationary plates 3 and movable or adjustable plates 4, the former being mounted upon one or more posts 5 supported upon the panel 1.

The movable or adjustable plates 4 of the condenser are mounted upon a rotatably adjustable shaft 10 the front end of which projects through an opening 11 in the panel 1 and is provided with a dial 12 having a scale thereon as usual. The shaft 10 is provided inwardly of the panel 1 with a gear 15 of relatively large diameter which is adapted to rotate with the shaft when the latter is rotatably adjusted. A small gear or pinion 17 is supported upon a short shaft 18 a distance from and in parallel relation to the shaft 10. The shaft 18 is rotatably mounted in an opening 19 through the panel 1. Its front end projects through said opening and is provided with a knurled finger piece 20 by means of which the said shaft may be rotated. An idler gear is mounted upon a shaft or support 24, supported at its opposite ends upon plates 25 and 26 supported and held in spaced relation to each other in the manner as indicated. These plates are provided with openings 30 and 31 through which the shafts 10 and 18 extend. The said shafts constitute the supports for the said plates. These plates are provided with inwardly extending flanged projections as indicated at 32 and 33 which are secured together by fastening means indicated at 34. It will be observed that the shaft 18 on which the small pinion 17 is mounted is located in a horizontal plane a considerable distance below that in which the shaft 10 is located and that the frame-like structure comprising the plates 25 and 26 is inclined upwardly at an angle of approximately forty-five (45) degrees, as indicated in Fig. 1 of the drawing.

The plate 26 is provided at its lower end with a projection 40 to the outer end of

which the lower end of a coiled spring 41 is connected. The upper end of said spring is connected to an extension from the lower pivoted end of a lever arm 43. The said pivoted end of the lever arm 43 is mounted upon a screw stud 44 which is secured to the plate 26 at a point below but in adjacent relation to the shaft 10. The lever arm 43 extends underneath and beyond the shaft 10. 10. The spring 41 tends to hold the arm 43 in its uppermost position. The said arm 43 is provided at a point near its pivot and forwardly thereof with a lateral projection 45, the top side of which is adapted to engage the outer curvilinear surface of the cam member 48 mounted upon the shaft 10. The said cam member is located between the plates 25 and 26. In Fig. 1 the cam is shown in such position that the lever arm 43 20 is allowed to occupy its uppermost position under the influence of the spring 41. Rotation of the shaft 10 and of the cam 48 carried thereby to the right or in clockwise direction effects depression of the lever arm 25 43 so as to cause downward vertical movement of an indicating device 50 supported upon the outer end thereof. The said device comprises pointers or indicators 51 which project in opposite directions and is 30 provided with a stem 52 which projects through and is slidable within a slot 53 extending longitudinally of the outer end portion of the said arm 43. The arm 43 is located inside of the panel 1 and the outer 35 slotted end portion is located in juxtaposition to the inner surface of said panel. The stem 52 extends through a vertical slot 55 in the panel 1 and moves up and down therein as the arm 43 is oscillated upon its pivot. 40 At about the time the arm 43 has reached its lowest position the projection 45 escapes from the surface of the cam 48 and under the influence of the spring 41 is quickly returned to its highest position. 45 Mounted upon the outside of the panel 1 is a label or card holding device which is of rectangular shape and is provided with card or paper holding openings 60 and 61. These openings 60 and 61 are separated by a central vertical strip 62 provided with a slot 63 which registers with the slot 55 in the panel 1. The stem 52 of the indicator 50 extends through not only the slot 55 but also the slot 63. 50 It will be understood that as the lever arm 43 oscillates upon its pivot 44 the indicator 50 is reciprocated in the slots 55 and 63 so that the indicating points 51 thereof cooperate with cards or sheets of paper 65 mounted with the said label holding device. The latter is secured to the outer or front side of the panel 1 by means of screws 66. 60 In the employment of a radio signal receiving apparatus provided with my invention for the interception and receiving of

electric waves from distant broadcasting stations it will be necessary to adjust the condenser so as to adapt it for the interception of waves of the particular frequency which may be radiated from a particular broadcasting station. Such adjustment is first effected by the rotation of the dial 12. By the manipulation of this dial an approximate adjustment is first obtained. For a further and more refined adjustment the pinion 17 may 75 be adjusted by rotating the knurled finger piece 20 which operates through the idler gear 22 to impart fine rotative adjustments to the gear 16 and the shaft 10 to which the said gear is rigidly secured. The adjustment of the shaft 10 and the condenser 48 carried thereby operates to accurately adjust and position the indicator 50 with the pointers 51 thereof in co-operative relation with respect to the cards or strips of paper 80 65. The position of either one of these pointers at such time may be recorded by writing opposite the same the letters or other data which will serve to designate the particular broadcasting station from which at 85 that time the electric waves were received.

The word "distant" employed in the specification and claims with respect to sending or broadcasting stations is intended to refer to stations which are located both nearby and far away. 90

Having thus described my invention, what I claim and desire to secure by Letters Patent is:

1. Station recording means for radio signal receiving apparatus comprising, in combination, a device which is adjustable to adapt said apparatus to intercept electric waves from distant stations, rotatable means for adjusting said device, an indicating device, a pivoted lever upon the outer end of which said indicating device is mounted, the pivot for said pivoted lever being located beyond the said rotatable means from the said indicating device and below the same, and means carried by said rotatable device for effecting pivotal movement of the said lever to thereby effect reciprocating movements of the said indicating device. 100

2. Station recording means for radio signal receiving apparatus comprising, in combination, a device which is adjustable to adapt said apparatus to intercept electric waves from distant stations, rotatable means for adjusting said adjustable device, a lever pivoted in juxtaposition to the said rotatable means, the said lever extending from its pivot beyond the said rotatable means, yielding means tending to cause pivotal movement of the said lever toward said rotatable means, means carried by said rotatable means for engaging said lever and effecting pivotal movement thereof, indicating means mounted upon the outer end of said lever, and means associated with the 105 110 115 120 125 130

said indicating means whereby the position of the latter at any desired adjustment of the said adjustable device may be recorded.

3. Station recording means for radio signal receiving apparatus comprising, in combination, a device which is adjustable to adapt the said apparatus to intercept electric waves from distant broadcasting stations, a rotatable shaft for adjusting said 10 adjustable device, a lever pivoted at one end in adjacent relation to said shaft, the said lever extending transversely of and beyond said shaft and being provided with a slot extending longitudinally of its outer end portion, an indicating device slidably mounted within said slot, means carried by said 15 rotatable shaft for effecting pivotal movements of the said lever, means whereby said indicating device may be caused to move in a vertical plane, and means associated with 20 said indicating device whereby the position of the same at any desired adjustment of the said adjustable device may be recorded.

4. Station recording means for radio signal receiving apparatus comprising, in com- 25

bination, a device which is adjustable to adapt the said apparatus to intercept electric waves from distant stations, a rotatable shaft for effecting adjustment of said adjustable device, a lever pivoted at one end in adjacent 30 relation to said shaft which lever extends transversely of and beyond said shaft, a cam mounted upon said shaft, yielding means operating to hold a portion of said lever in yielding contact with the said cam whereby 35 upon rotation of the shaft and the cam carried thereby pivotal movement of the said lever is effected, an indicating device having slidable connection with the outer end portion of the said lever, vertically arranged 40 recording strips located in cooperative relation with respect to said indicating device, and means for causing the said indicating device to move in a vertical plane upon pivotal movement of the said lever. 45

In testimony that I claim the foregoing as my invention, I have hereunto signed my name this 6th day of December A. D., 1924.

ARNO ZILLGER.
